UNITED STATES PATENT OFFICE.

OLIVER PERRY ANDERSON, OF NASHVILLE, TENNESSEE.

ATTACHMENT FOR TYPE-WRITING MACHINES.

1,196,634.

Specification of Letters Patent. Patented Aug. 29, 1916.

Application filed October 19, 1915. Serial No. 56,763.

To all whom it may concern:

Be it known that I, OLIVER PERRY ANDERSON, a citizen of the United States, residing at Nashville, in the county of Davidson 5 and State of Tennessee, have invented certain new and useful Improvements in Attachments for Type-Writing Machines; and I do hereby declare the following to be a full, clear, and exact description of the invention, such as will enable others skilled 10 in the art to which it appertains to make and use the same.

This invention relates to an attachment for typewriting machines, and has for one 15 of its objects the provision of a device which can be readily applied to any of the standard typewriting machines now in use.

Another object of this invention is the provision of an attachment for typewriting 20 machines for preventing the casual displacement of the papers relative to each other while in the machine.

Another object of this invention is the provision of an attachment for typewriting 25 machines, provided with supporting members having means whereby the device can be readily attached to or detached from a typewriting machine when desired.

A further object of this invention is the 30 provision of an attachment for typewriting machines for preventing the casual displacement of the papers while in the machine, which is simple in construction, durable and efficient in use, and which can be manufactured and sold upon the market at a nominal cost.

These and other objects will be herein-after more clearly set forth in the following specification, the subject-matter of the 40 claims, and the views illustrated in the drawings, wherein similar reference characters denote corresponding parts throughout the several views, and in which,

Figure 1 is a perspective view of the invention, showing the same in attached position upon the paper shelf of a typewriting machine. Fig. 2 is a vertical transverse sectional view of the attachment, and the paper shelf and the platen of a typewriting machine, showing the detail construction and mounting of the device and the manner of positioning the papers therein at the beginning of the typewriting operation. Fig. 3 is a similar view to Fig. 2, showing the position the papers assume when the typewriting operation is partially completed.

Referring to the drawings, 1 denotes the platen, and 2 the paper shelf of a typewriting machine, the paper shelf 2 being provided with the slots 3, two slots being shown 30 though any desired number may be formed in the paper shelf 2.

The attachment consists of an open ended casing, formed of any suitable material and dimensions, and comprises the top wall 4, 35 the side walls 5, and the bottom wall 6, the end walls being omitted thus providing an open ended casing.

The bottom 6 of the casing is preferably formed of double thickness or layers, and interposed and embedded between the layers of the bottom 6 are the straight body portions 7 of the supporting strips or members, formed of any suitable material, preferably metal, or the body portions 7 of the supporting strips may, if so desired, be secured upon the upper side or the under side of the bottom 6 by the use of rivets or other suitable fastening means.

The ends of the supporting strips, which 40 project outwardly from the bottom 6 of the casing, are curved downwardly, as at 8, and of a contour to conform to the contour of the paper shelf 2 of the typewriter. The extremities of the curved end portions of the 45 supporting strips are bent inwardly at approximately right angles to provide the shoulders 9, and thence downwardly at approximately right angles to the shoulders 9, and approximately parallel to the downwardly curved end portions, to provide the lips 10.

In Figs. 2 and 3 of the drawings, 10a notes the top sheet of paper which is to be written upon, 12 the carbon paper, 13 the 45 carbon copy paper, 14 the bottom ends and 15 the top ends of the sheets of paper.

The application and operation of the attachment is briefly described as follows:— In applying the attachment to a typewriter, 50 the rear end of the casing is elevated in a manner so that the lips 10 of the supporting strips can be readily passed through the slots 3 of the paper shelf 2 from the front side of the paper shelf, and until the shoulders 9 of the supporting strips pass into the slots 3 of the paper shelf 2, whereupon the rear end of the casing is then lowered until the curved end portions 8 of the supporting strips snugly engage the front surface of the 55 paper shelf 2 above the slots 3, the shoulders 9 being seated in the slots 3, and the lips 10

engaging the rear surface of the paper shelf 2 below the slots 3, whereby the device is attached to the typewriter in secure operative position. The person operating the typewriter, after placing the sheets of paper 11, 12 and 13 in their proper position with respect to each other, now inserts the ends 14 of the sheets through the front open end of the casing, and into the casing, with the sheets 10 of paper resting upon the bottom 6 of the casing, and thereafter positions the upper ends 15 of the respective sheets around the platen 1 of the machine at the initial stage of the typewriting operation as shown in Fig. 2. After the typewriting operation has been partially completed, the person inserts the upper ends 15 of the respective sheets into the casing through its forward open end, the sheets of paper assuming the positions as shown in Fig. 3, it being obvious that as the typewriting operation further progresses the ends 14 are gradually drawn from within the casing and the ends 15 of the sheets further projected into the casing 25 by the platen, and this movement of the sheets of paper continue until the typewriting operation is completed.

From the foregoing, it is manifestly clear that by the use of my invention, casual 30 placement of the sheets of paper relative to each other, due to any cause, is impossible.

Having described my invention, what I claim as new and desire to secure by Letters-Patent, is:—

- 35 1. In a device of the class described, the combination with the platen of a typewriting machine, and the paper shelf thereof having a plurality of slots therein, of an open ended casing having solid top, bottom, and side 40 walls, and flexible supporting members carried by said casing for engaging the slots of said paper shelf for mounting said casing upon said paper shelf.
2. In a device of the class described, the 45 combination with the platen of a typewriting machine, and the paper shelf thereof

having a plurality of slots therein, of an open ended casing for receiving the ends of a plurality of sheets of paper actuated by said platen, and supporting strips carried 50 by said casing for engaging the slots of said paper shelf for attaching said casing in operative position upon said paper shelf.

3. In a device of the class described, the combination with the platen of a typewriting machine, and the paper shelf thereof having a plurality of slots therein, of an open ended casing for receiving the ends of a plurality of sheets of paper actuated by said platen, supporting strips carried by the 55 bottom of said casing, arms upon the projecting ends of said supporting strips, and means upon the extremities of said arms for engaging the said slots of said paper shelf for attaching said casing in operative position upon said paper shelf.

4. In a device of the class described, the combination with the platen of a typewriting machine, and the paper shelf thereof having a plurality of slots therein, of an 60 open ended casing for receiving the ends of a plurality of sheets of paper actuated by said platen, elongated supporting strips carried by the bottom of said casing and projecting outwardly therefrom, downwardly 65 curved arms upon the projecting ends of said supporting strips for engaging the front surface of said paper shelf, a shoulder adjacent the ends of said arms for seating in the said slots of said paper shelf, and a tongue extending from said shoulders for engaging the back of said paper shelf, whereby to attach said casing in operative position upon said paper shelf.

In testimony whereof I have signed my 85 name to this specification in the presence of two subscribing witnesses.

OLIVER PERRY ANDERSON.
